Inventor
Benjamin Nott

United States Patent Office.

BENJAMIN NOTT, OF ALBANY, NEW YORK.

Letters Patent No. 99,339, dated February 1, 1870.

ILLUMINATOR FOR STOVES, &c.

The Schedule referred to in these Letters Patent and making part of the same.

Be it known that I, BENJAMIN NOTT, of the city and county of Albany, and State of New York, have invented a new and useful Improvement in the Construction of Illuminators as Applied to Stoves, Furnaces, Ranges, Grates, &c.; and I declare the following specification, with the drawings accompanying the same, and forming part thereof, to be a full and complete description of my invention.

Figure 1 represents a form of rosettes in sections.

Figure 2 represents a sectional view of a corrugated illuminator.

Figure 3 represents a sectional view of a semi-cylindrical transparent of an illuminator, which may be plain, corrugated, or otherwise.

Figure 4 represents a sectional view of less, and may, if wished, be more than a semi-cylindrical transparent of an illuminator, and which may also be plain, or otherwise.

Figure 5 represents a sectional view of a convex transparent of an illuminator.

Figure 6 represents a sectional view of a concave transparent of an illuminator.

Figure 7 is a perspective view of a frame to hold in place the transparencents of an illuminator, which may be attached to a stove, or be used as a door, or part of a door to the stove, &c.

Figure 8 represents a sectional view of a plano-concave transparent.

Figure 9 represents a sectional view of a double convex transparent.

Figure 10 represents a sectional view of a double concave transparent.

Figure 11 represents a sectional view of a triangular transparent.

Figure 12 represents a sectional view of a triangular transparent with convex sides.

Figure 13 represents a sectional view of a triangular transparent having concave sides.

Figure 14 represents a double and a single plate illuminator.

Figure 15 represents a view of a translucent or transparent made in blocks or parts.

Figure 16 represents a view of a translucent or transparent in a globular form.

My invention consists in certain improvements in the forms of illuminators for stoves, furnaces, &c., made from glass or other translucent factitious substance, for which Letters Patent have already been granted to me, in combination with suitable holders or frames.

A, in the drawings, represents bars, blocks, and spheres of glass, made in various ornamental forms, whereby the appearance of the stove is greatly enhanced.

B represents similar forms, made hollow or tubular, to admit of the passage of air, and thus equalize the temperature of the sides.

Having thus described my invention,

What I claim as new, and desire to secure by Letters Patent, is—

Illuminators for stoves, furnaces, &c., made of glass or other translucent factitious substance, in the forms herein shown, in combination with a suitable frame, as described.

BENJAMIN NOTT.
